UNITED STATES PATENT OFFICE.

ALONZO W. GEARHART, OF FRESNO, CALIFORNIA.

HYDROCARBON-BURNER.

1,355,958.

Specification of Letters Patent. Patented Oct. 19, 1920.

Application filed February 20, 1920. Serial No. 360,138.

To all whom it may concern:

Be it known that I, ALONZO W. GEARHART, a citizen of the United States, and resident of Fresno, in the county of Fresno and the 5 State of California, have invented a new and useful Improvement in Hydrocarbon-Burners, of which the following is a specification.

My invention relates to a hydrocarbon 10 burner for gasifying and burning low grade fuel oils for use in stoves, furnaces and like places where it is desired to create heat. This invention is an improvement on that certain hydrocarbon burner for which a Patent 15 No. 860,460 was issued to me on July 16, 1907.

The objects of the invention described herein is to provide a burner having a frame support arranged so that a brick wall can 20 readily be built around it, having an oil feed which will not readily clog up when cleaning carbon from the burner, to produce a box for the burning fuel which will not permit the oil to waste into the ash pan, 25 and which will direct the flame so that the upper portion of the burner will not become super heated. Other objects have been accomplished which will hereinafter appear.

In the drawing accompanying this specification and hereby made a part hereof, Figure 1 is an isometric view of the burner complete. Fig. 2 shows a pipe draft flue. Fig. 3 is a frame support for the front wall 30 of the burner. Fig. 4 is a sectional view of the front plate. Fig. 5 is a sectional view of the burner installed with a baffling wall to direct the movement of flame and heat. Fig. 6 shows the burner installed in a fire box with a top plate to spread the heat.

40 The burner comprises a body portion or mixing chamber consisting of two parallel sides 2 and 2^a, a back end 3 of approximately the same height as the sides, and a bottom, or burning plate 4. The sides and 45 back are made the same height to prevent the fuel from overflowing. The plane of the end 3 and the plane of the bottom 4 adjacent thereto forms an acute angle. The portion 4^a of the burning plate opposite to 50 the end 3 flares upward, preferably terminating with an upward curve. Directly above portion 4^a is a flue plate 5 which extends from the side 2 to side 2^a, dropping downward in an oblique direction, and terminating at the lower end with a portion 5^b 55 extending parallel with the bottom 4. 5^a is

the extreme upper portion of the flue plate 5 which appears as a bar on the top of sides 2 and 2^a, and connecting said sides together. The formation described leaves an opening 60 between the flaring portion 4^a and the flue plate 5 which can be termed the lower draft flue B. 7 is a fuel or oil supply pipe which should pass through the burning plate within the flue B. Fuel pipe 7 should enter the 65 flue through a vertical hole 7^a. In my former patent referred to the fuel pipe was placed at a slight angle from a horizontal line and in cleaning the burning plate by scraping, the fuel pipe was frequently 70 clogged up whereas by making the said opening vertical the scraper can be dragged over it without pulling much carbon therein.

6 and 6^b are parallel flanges on sides 2 and 2^a, forming an oblique slideway 6^a directly 75 back of bar 5. C is a front support constructed with two uprights 9 and 9^a having a top plate 8 connecting them on the top. The lower ends of uprights 9 and 9^a are reduced so they will fit in slideways 6^a. D is 80 the front plate and when the burner is assembled it rests on the top of bar 5^a and leans against the support C and toward the back of the burner. This form is substituted for the flanges in my former patent 85 which were bolted to the walls of the stove, as it has been found advisable to have the front wall leaning in this manner and to have the entire construction of more rigid material than the stove walls are usually 90 made of, and to have the front removable. Further, in bricking a burner in a furnace the top plate 8 forms a base on which brick 95 can rest. The front plate D has an oblique hole 10 through the approximate center into which a draft pipe E is fitted. This pipe should be easily removable and should normally remain in place when adjusted. To accomplish this I have formed a reduced portion 11 which easily passes through the 100 hole 10, and have constructed a stop 12 on the top end of the pipe so when assembled the reduced end can be stuck through hole 10 and gravity will hold the lower end down so that stop 12 on the upper end will engage 105 the wall and prevent the pipe from slipping out. In my former construction the current of air passing through the upper draft was directed so a back draft was created and the pipe conducting the draft was frequently 110 unduly heated. In the present invention I have formed the upper draft pipe

E straight, and its oblique position drives the air toward the back of the burner. The combination of the upper and lower drafts as thus arranged prevents the intense heat 5 from coming toward the front of the burner.

In Fig. 6 I have shown the burner installed in a fire box preferably constructed of fire brick. This box should be built up on the two sides of the burner, extending to 10 the top, designated on the drawing as H and H¹, and having a back baffling wall F which is constructed to angle upward and outward, and to the same height as the side walls. At each corner on the top of the fire 15 box I have placed an upright post 13, 13^a, 13^b and 13^c which support a baffling plate or heat spreader G.

F is a baffle wall which directs the currents of heated air from the upper and 20 lower drafts upward as it leaves the mixing box.

In using this burner a small quantity of oil is admitted to the burning plate, and 25 ignited in the usual manner, thus heating the plate, when the oil can be turned on in larger quantities and the heated plate and oxygen from the air drafts will form a hot fire and heat the stove or furnace readily.

I claim as new and ask for Letters Patent:

1. In a burner of the character described the combination of a burner plate, a frame around the burning plate, a front portion extending upward above the frame, a fuel 30 lead, a lower draft disposed at the front end of the burner and an upper draft composed of a straight pipe extending through 35 the front wall obliquely and pointing toward the approximate center of the burner 40 plate, substantially as described.

2. In a hydrocarbon burner, the combination of a noncombustible box having a bottom, parallel vertical sides, a rear end of the same approximate height disposed so the 45 upper portion leans inwardly, a baffle wall above the rear end constructed to lean outwardly, a front end to said box having an upper draft and a lower draft, the line of 50 said drafts being adapted to meet at an acute angle at the approximate center of the bottom of the box and a fuel feed opening in the path of the lower draft, substantially as described.

3. In a hydrocarbon burner the combination of a noncombustible box having an 55 open top, a baffle wall at one end extending upward and outward from a perpendicular line, and a lower and an upper draft opening adapted to direct currents of air so they 60 will meet on the upper surface of the bottom of the box at the approximate center thereof, said currents meeting at an acute angle, and a fuel intake opening consisting of a vertical hole through the bottom of the 65 box in the line of the lower draft.

4. In a hydrocarbon burner the combination of a noncombustible box having two sides, two ends and a bottom, one of said ends extending above the other end and sides, an opening for an under draft in a 70 line adjacent to the top plane of the bottom of the box, a fuel feed opening through the bottom in the line of said under draft, and an upper draft consisting of a straight pipe projecting obliquely through the extended 75 end, and adapted to direct a current of air obliquely to the approximate center of the bottom of the box substantially as described.

5. In a hydrocarbon burner in combination with a fire box closed on four sides, having an opening for gas and heated air on the upper side thereof, of a noncombustible auxiliary box having an open top, a baffle wall at the back end extending beyond the 80 top of the auxiliary box, two openings in the wall opposite the baffle plate having draft leads to the interior of the auxiliary box, said draft leads being adapted to direct one current of air to pass along the bottom 85 of the auxiliary box toward the center of the bottom of the auxiliary box, and a fuel lead in the path of the lower draft.

6. In a hydrocarbon burner, the combination of a noncombustible box having a bottom, parallel vertical sides, a rear end of the same approximate height disposed so the upper portion leans inwardly, a baffle wall above the rear end constructed to lean outwardly, a front end to said box having an upper draft and a lower draft, together with 95 a baffle plate supported so it covers the box with openings between the top walls of the box and the baffle plate, substantially as described.

7. In a hydrocarbon burner in combination, a fire box inclosed on four sides and on the bottom, fuel and air inlets on one side thereof, noncombustible auxiliary walls surrounding the fire box on three sides other 100 than the side having the fuel and air inlets, a baffle wall at the back end extending beyond the top of the auxiliary box, two openings in the wall opposite the baffle wall having draft leads to the interior of the fire 110 box, said draft leads being adapted to direct one current of air to pass along the bottom of the fire box toward the end having the baffle wall, one current to pass from the end opposite the baffle wall obliquely toward 115 the center of the bottom of the fire box, and a spaced horizontal partition extending from one side to the other of the fire box between the upper and lower drafts, a fuel lead opening in the path of the lower draft substantially 120 as described.

8. In a hydrocarbon burner, in combination, a fire box inclosed on four sides, a closed bottom and an open top, fuel and air inlets adjacent to one of said sides, herein 130

called the front, a noncombustible auxiliary box surrounding the fire box on the three sides except the front, and extending uniformly above the top of the fire box, the wall 5 of the box opposite the front leaning outwardly, upright noncombustible posts at each of the four corners of the auxiliary box, and a baffle wall set horizontally on the top

of said posts a spaced distance from the top of the wall of the auxiliary box, substantially as described. 10

ALONZO W. GEARHART.
